United States Patent Office

Des. 206,518
Patented Dec. 27, 1966

206,518

IDENTIFICATION CARD HOLDER

Pearl S. Evans, 402 Belknap Place, Keokuk, Iowa 52632

Filed Feb. 28, 1966, Ser. No. 1,209

Term of patent 7 years

(Cl. D1—3)

FIG. 1

FIG. 3

FIG. 2

The dominant features of my design reside in the portions shown in full lines.

I claim:

The ornamental design for an identification card holder, as shown and described.
